GOLF BALLS

Louis F. Muccino, Rye, N. Y.

Application December 22, 1953, Serial No. 399,714

3 Claims. (Cl. 273—227)

This invention relates to golf balls.

This application is a continuation in part of my copending application Serial No. 384,421, filed October 6, 1953, and since abandoned.

The characteristics and construction of modern golf balls are controlled to a large extent by the rules of the official organizations which govern and control tournament play such as the United States Golf Association and the Professional Golfers Association, as well as by the habits, customs, preferences and prejudices of large numbers of experienced golf players.

Thus, by official rule the diameter of a tournament golf ball may not be less than 1.68 inches, and must weigh less than 1.62 ounces. Experience has shown that the nearer balls conform to these minimum and maximum limitations of diameter and weight, respectively, the longer their flight, assuming always that balls are of generally similar construction and are tested under identical conditions. Thus, a ball having a diameter of 1.68 inches which weighs only 1.50 ounces would, when tested under identical conditions, travel less distance than a ball of equal diameter and of similar construction which weighs the maximum permissible weight of 1.62 ounces. Consequently golf ball manufacturers, always seeking to produce balls which will travel the maximum distance, design their balls to approach these minimum and maximum limitations as closely as possible. A ball of maximum weight and minimum diameter has a specific gravity of approximately 1.25. And since the specific gravity of both rubber and balata which are the principal constituents of golf balls is less than 1, it is obvious that constituents of higher specific gravity must somehow be incorporated in the ball if it is to achieve maximum permissible weight.

When we consider the requirements of golf players, the primary demand, of course, is for a "long ball." Other things being equal, a ball which will consistently travel a few yards further than its competitor will always be chosen. Balance, i. e. the uniform distribution of weight with respect to the geometric center of the ball, is also important. An unbalanced ball will tend to deviate from the intended line of flight, giving the effect of a "slice" or "hook," even though the ball may have been hit accurately. But when we depart from the factor of distance, which is accurately measurable, and the factor of balance, which is easily determinable, we approach a region of requirements which are somewhat mysterious in character since they are recognizable only in the actual performance of a ball and testable only by the individual golfer's reactions when the ball is driven. We refer to such characteristics or qualities as "click," i. e. the sharp sound of the impact of the club head against the ball, "feel," i. e. that which the golfer feels when the ball is struck, and "lift" or "rise" which has to do with the trajectory of the ball. A ball which "rises" properly follows a somewhat higher trajectory than otherwise. There is, so far, no adequate scientific explanation of

2

these qualities, or of the constructional characteristics which produce them. But they are known to every experienced golfer and greatly influence the selection of balls.

The problem of the manufacturer of golf balls is to produce a ball which falls within the official requirements as to diameter and weight, and which achieves maximum flight within those limitations. Since this implies using the maximum permissible weight, the problem is complex, because experience has proven that the addition of the constituents of high specific gravity required to attain maximum weight almost inevitably affects adversely some other desired quality such as balance, click, feel, or rise.

It is an object of the present invention to provide a solution for this problem.

15 Other objects and advantages of the invention will appear hereinafter.

A preferred embodiment of the invention selected for purposes of illustration is shown in the accompanying drawings, in which the figure is a vertical cross section 20 through a golf ball.

In the following specification, the usual terminology of the industry will be adopted and used as follows:

A "golf ball" will be defined as a complete, finished ball, ready for play, comprising a balata (or gutta percha) 25 cover, windings of rubber thread, or tape, or both, and a core. The cover is usually coated with paint, enamel or lacquer.

A "center" will be defined as a golf ball from which the cover has been removed.

30 A "core" will be defined as an object, usually spherical, about which the windings are wound. In the case of a hollow core, the wall of the core which surrounds the cavity will be referred to as the core envelope.

In the past various expedients have been adopted as a 35 means of increasing the specific gravity and weight of golf balls, and other expedients have been adopted in an effort to satisfy one or more of the other requirements demanded by golfers. At various times and in various types of balls powdered constituents of high specific 40 gravity such as litharge, barium sulphate, zinc oxide and the like have been incorporated in the cover, or in the rubber thread or tape, or in the core, or in all three.

The core of a golf ball is almost always made of rubber, sometimes solid and sometimes hollow. When hollow, 45 the cavity has sometimes been filled with a solid object of high specific gravity such as steel or lead to provide the desired increase in weight. At other times the cavity has been filled with liquid, paste, or gelatinous material, and frequently weighting constituents have been added to or 50 incorporated in the liquid, paste, or gelatinous material to provide the desired increase in weight.

According to the present invention I utilize a hollow core of resilient, elastic material such as rubber and I fill the core cavity with a multiplicity of discrete metallic 55 particles ranging in size from metallic powder to small metal particles. Because of the high specific gravity of lead, I prefer to use metallic lead in the form of lead powder or in the form of small lead pellets, such, for example, as spherical lead shot. Preferably the volume 60 of the cavity is calculated to be just sufficient to hold the metal required to supply the additional weight. A cavity having a diameter of from $\frac{3}{8}$ " to $\frac{1}{2}$ " will ordinarily be found satisfactory to accommodate sufficient metallic particles to give the desired increase in weight, the exact diameter being dependent on whether the core envelope or any other part of the ball contains weighting material. If metal particles of lower specific gravity are used, a cavity of somewhat larger volume will be required.

It is my theory that the use of a large number of small discrete metallic particles permits the core to be deformed when the ball is struck in much the same manner that a liquid filled core may be deformed. There-

fore, the use of a few metallic particles of large size which would tend to lock themselves in fixed position within the cavity is precluded. In general, at least a dozen particles are required, and in using the phrase "a multiplicity of particles," I intend to indicate a number in excess of this. Indeed, for best results, I prefer to use lead particles ranging in size from 100 mesh powder to spherical lead shot having a diameter not exceeding .080" in which case the number of particles greatly exceeds twelve.

The wall thickness of the core envelope may be varied, as desired, depending on several considerations. For best results, I prefer to use a relatively thin wall, as from $\frac{1}{16}$ " to $\frac{3}{16}$ ", so as to keep the diameter of the core as small as possible, thus increasing the amount of wound rubber tape or thread in the wall. However, if the diameter of the cavity is $\frac{7}{16}$ ", which I have used successfully, and if the wall thickness of the core envelope is $\frac{1}{8}$ ", which I have also used successfully, the diameter of the core will be only $\frac{11}{16}$ ". Many golf ball winding machines are incapable of winding so small a core. In such cases, the wall thickness of the core envelope may be increased, as necessary, for winding purposes. Other factors which may influence the wall thickness of the core envelope are the matter of securing adequate adhesion of the two hemispherical cups of which the core envelope is customarily formed, and the matter of securing sufficient rigidity of the core, by freezing, to permit winding of the tape or thread thereon. The thinner the wall of the core envelope, the less rigidity is imparted by freezing, and in some cases, the wall thickness must be increased to secure the desired rigidity.

In the preferred form of the invention the metal particles are inserted alone in the cavity, and no liquid, paste or other substance is included for it appears to be advantageous to have the interstices between the particles filled with air which is compressible rather than with an incompressible liquid. However, in some cases, the use of a small quantity of liquid such as water which may easily be frozen may be desirable as a means of obtaining a rigid core for winding without increasing the wall thickness of the core envelope. The use of such liquid also has some lubricating value which aids the relative movement of the particles when the ball is deformed when struck. In all cases, however, the metallic particles are in contact with and support each other within the cavity. They are not suspended in or supported by liquid and the quantity of liquid, if any, is less than sufficient to fill the cavity.

Referring to the drawings, the rubber core envelope 1 is here shown as having a relatively thin wall. The core cavity 2 is filled with a multiplicity of metallic particles 3, preferably lead shot having a diameter of approximately .04".

The core is completely encased by a thick layer 4 of 55 rubber tape or thread which is wound around the core under rather heavy tension in accordance with usual practice. The resulting center is then covered by a cover

5 of balata or gutta percha which is molded under heat and pressure in accordance with usual practice.

I am aware of Knight U. S. Patent No. 1,192,831 which discloses what is frequently known as a "liquid center" ball in which a spherical rubber bag at the center of the ball is filled with liquid. The bag also contains "one or more balls which are free to move about in the liquid contained in the playing ball and which balls have a specific gravity greater than said liquid." One of the 10 objects of having the ball or balls of the patent "free to move about in the liquid" is to increase the back-spin effect, and freedom to move is the sine qua non without which this effect cannot be increased. The patented ball is, therefore, different both structurally and in function from the ball of the present invention.

I am also aware of Evans et al. U. S. Patent No. 1,530,820 which discloses a ball having a "center" consisting of a spherical rubber envelope containing powdered metallic lead distributed throughout a liquid (a glue-glycerine compound) of such high viscosity as to maintain the lead in suspension. In the patented ball, the liquid medium supports the lead particles, and said particles are not in contact with each other and do not support each other within the cavity.

25 It will be understood that the invention may be variously modified and embodied within the scope of the subjoined claims.

I claim as my invention:

1. A golf ball of not less than 1.68" outside diameter comprising, in combination, a spherical hollow core envelope having a cavity therein, the outside diameter of said hollow core envelope being not greater than $\frac{11}{16}$ ", a layer of rubber strands wound under tension around said core envelope to provide a center of not less than 30 1.5", a cover of no greater than usual thickness surrounding said layer of rubber strands, whereby the thickness of said layer of rubber strands lying between the core envelope and cover is greater than usual, and a multiplicity of discrete metallic lead particles filling the cavity of 35 said hollow core envelope, said particles being in contact with and supporting each other within the cavity, the quantity of lead particles in said cavity being sufficient to bring the total weight of the ball to approximately the maximum permissible weight of 1.62 ounces.

2. A golf ball according to claim 1 in which said particles are spherical lead pellets.

3. A golf ball according to claim 1 in which the wall thickness of said hollow core envelope is not greater than $\frac{1}{8}$ " and the diameter of said cavity is not in excess of $\frac{7}{16}$ ".
